(57) **CLAIM**

The ornamental design for a system of hair washing sinks, as shown and described.

DESCRIPTION

FIG. 1 is a perspective downward-looking view of a first exemplary embodiment of system of hair washing sinks in accordance with the present invention;

FIG. 2 is an elevational front view of the system of hair washing sinks of FIG. 1;

FIG. 3 is an elevational rear view of the system of hair washing sinks of FIG. 1;

FIG. 4 is an elevational left-side view of the system of hair washing sinks of FIG. 1;

FIG. 5 is an elevational right-side view of the system of hair washing sinks of FIG. 1;

FIG. 6 is a top view of the system of hair washing sinks of FIG. 1;

FIG. 7 is a bottom view of the system of hair washing sinks of FIG. 1;

FIG. 8 is a perspective downward-looking view of a second exemplary embodiment of a system of hair washing sinks, illustrating that the system of hair washing sinks may include any number of additional identical hair washing sinks between the broken lines, in accordance with the present invention;

FIG. 9 is an elevational front view of the system of hair washing sinks of FIG. 8;

FIG. 10 is an elevational rear view of the system of hair washing sinks of FIG. 8;

FIG. 11 is a top view of the system of hair washing sinks of FIG. 8; and,

FIG. 12 is a bottom view of the system of hair washing sinks of FIG. 8.

The left and right elevational views of the second embodiment of the system of hair washing sinks is identical to the left and right elevational views of the first embodiment of the system for hair washing sinks.

The broken lines in the drawings represent environment and boundaries of the system of hair washing sinks and form no part of the claimed design.
